CLAIM

The ornamental design for a seating unit, as shown and described.

DESCRIPTION

FIG. 1 is a front perspective of a seating unit showing my new design;

FIG. 2 is a right side view of the seating unit, the left side view of the seating unit being a mirror image of the right side view;

FIG. 3 is a top view of the seating unit;

FIG. 4 is a front elevational view of the seating unit; and,

FIG. 5 is a rear view of the seating unit.
